Att'y's.

UNITED STATES PATENT OFFICE.

LUTHER L. DAVIS, OF NEWTON, MASSACHUSETTS, ASSIGNOR, BY MESNE ASSIGNMENTS, TO RAND KARDEX BUREAU, INC., OF TONAWANDA, NEW YORK, A CORPORATION OF DELAWARE.

DESK.

Application filed November 3, 1924. Serial No. 747,429.

This invention relates to desks adapted to be used in connection with typing machines having a traveling carriage and objects of the invention are to provide a small 5 compact desk for use in connection with machines having a traveling carriage constructed in such a manner that such machine can be moved in close proximity thereto without obstructing the movement of the carriage; 10 to provide means associated with a sliding shelf to prevent papers from being swept into the desk when the shelf is moved into a position out of use; and to provide a desk having the new and improved features of construction hereinafter pointed out.

One embodiment of the invention is illustrated on the accompanying drawings in which—

Fig. 1 is a top plan view of the desk; 20 Fig. 2 is a front elevation of the desk; and Fig. 3 is a section on the line 3—3 of Fig. 2.

The embodiment of the invention illustrated comprises a desk of sheet metal or 25 wood although sheet metal is preferred owing to its strength and fire-resistant qualities. The desk consists of a substantially rectangular flat top 1 which is supported by legs 2 and suitable panels (not shown) close 30 three sides. Slidable in the desk are drawers 3 which may be of different construction to accomodate articles of different sizes, each drawer having a handle 4 and a label holder 5 for identifying the contents of the 35 drawers.

Slidable into and out of the desk between the top drawer and the top 1 is a sliding shelf 6 which is spaced from the top 1 by a spacer plate 7 having an inturned flange 40 8. To prevent papers from being carried into the desk when the shelf is moved into a position out of use a wiper 9 of felt or other suitable materials is fastened to the under side of the flange 8, so that when 45 the shelf 6 is moved inwardly into a position out of use papers on the desk will come in contact with the wiper and thus be prevented from being carried inside the desk where they would be in danger of being lost.

For supporting a typing machine B a shelf 10 is shown secured in any suitable manner to the side of the desk, the outer end thereof being supported by legs 11 which may be suitably braced by braces 12. Mani-

festly the machine B may be mounted on 55 a suitable carriage or frame if desired to be moved away from the desk.

Integral with the top 1 is an extension 13 which is flush with the upper surface of the top and is of less depth than the depth 60 of the top from front to rear. It will at once be apparent that a typing machine B may be placed in close proximity to the extension 13, the carriage being enabled to move toward the desk past the rear end of 65 the extension 13 so that the operator positioned in front of the desk can conveniently use the top of the desk while at work. As above mentioned such machine may be supported upon the shelf 10 or in any other 70 desired manner. To prevent papers from being accidentally displaced from the top 1 of the desk and extension 13 an upright guard rail 14 partially surrounds the top and extension and may be secured to the 75 sides thereof in any suitable manner. Cups or receptacles 15 for pins, clips, sponges, etc. may be attached to the rear portion of the extension 13 if desired.

As indicated in the drawings the depth 80 of the extension 13 from front to rear is approximately equal to the depth of the support for the typing machine B. Thus it will be observed that the operator of the machine B in front of the machine is conveniently positioned near the top of the desk as well as the drawers 5 which can be moved in and out without interference by the operator. By virtue of such construction the machine operator does not have to assume 90 a cramped or uncomfortable position which has been necessitated heretofore in many instances in the operation of bookkeeping and adding machines.

An outstanding characteristic of the invention consists in the provision of a desk the top of which is recessed to provide an extension of less depth than the depth of the desk from front to rear whereby a typing machine can be moved into close proximity 100 of the desk with its traveling carriage movable into the space defined by the end of the desk and the rear of the extension. A further important feature comprises a wiper 105 associated with the sliding shelf to prevent papers from being carried inside the desk when the shelf is moved into a position out of use.

It is to be understood that the embodiment of the invention shown is given merely by way of illustration and numerous changes in details of construction, arrangement and selection of materials may be made without departing from the spirit of the invention especially as defined by the appended claims.

I claim:

1. In a desk or the like, having a sliding shelf, the combination of a sliding shelf and yielding means on the desk, to engage the upper surface of the shelf and prevent papers from being carried inside the desk when the shelf is moved inward.
- 10 2. In a desk or the like having a sliding shelf, the combination of a sliding shelf, a chamber in the desk to receive the same,

and yielding means on that portion of the desk defining the outer portion of said chamber, to engage the upper surface of the shelf and prevent papers thereon from being carried inside the desk.

3. In a desk or the like having a sliding shelf, the combination of a sliding shelf and a strip of soft matted material on said desk to engage the upper surface of the shelf whereby when the shelf is moved from outward to inward position the strip prevents papers on the shelf from being carried inside the desk.

Signed by me at Cambridge, Massachusetts this 27th day of October 1924.

LUTHER L. DAVIS.
